SLICING MACHINE

William J. Campbell, Indianapolis, Ind., assignor
to American Slicing Machine Company, Chi-
cago, Ill., a corporation of New York

Application November 18, 1938, Serial No. 241,176

4 Claims. (Cl. 146—102)

My invention relates to an improvement in slicing machines and has for one purpose the provision of means for maintaining a true gauge of the slices.

Another purpose is the provision of means for preventing unintended rearward movement of the gauge plate of a slicing machine.

Another purpose is the provision of guiding means which shall be effective to permit intended movement of a gauge plate toward and away from the cutting plane of a knife, while preventing undesired movement, bowing or tilting, in response to the thrust of the work against the forward face of the gauge plate.

Another purpose is the provision of means for constraining the gauge plate to movement along a path at an angle to the angle of thrust of the work against the gauge plate, whereby the guiding means for the gauge plate serves as a positioning abutment resisting movement of the gauge plate in response to the thrust of the work.

Other purposes will appear from time to time in the course of the specification and claims.

I illustrate my invention more or less diagrammatically in the accompanying drawings wherein:

Fig. 1 is a front elevation;

Fig. 2 is a plan view with parts broken away and parts in section;

Fig. 3 is a partial horizontal section of the structure shown in Fig. 2, with the parts in a different position;

Fig. 4 is a partial front view of a variant form of the device;

Fig. 5 is a section on the line 5—5 of Fig. 4; and

Fig. 6 is a section similar to Fig. 5 through a variant form of the device.

Like parts are indicated by like characters throughout the specification and drawings.

Referring to the drawings, I generally indicate a base structure, such base having an upward extension as at 2, in which is housed the knife shaft 3 carrying the pulley 4 for the belt 5, extending to the motor pulley 6. 7 indicates a motor.

8 indicates a rotary knife mounted on the shaft 3 unitarily with the pulley 4, it being understood that in response to the rotation of the armature of the motor 7 the rotary knife is rotated. The forward face of the knife is partially masked by the guard plate 9, which forms no part of the present invention.

10 indicates a gauge plate which has secured to a lower portion thereof, at a level within the base portion 1, a forward extension or structure 11. This in turn is secured to a transversely extending portion 12 which carries a long sleeve 13 at one end and a short sleeve 14 at the opposite end. The sleeves 13 and 14 are slidably mounted upon horizontal pins 15, 16 within the base 1,

and located forwardly of the cutting plane of the knife.

17 is an exterior handle in communication with the lever structure 18, the details of which do not of themselves form part of the present invention. It will be understood, however, that in response to the movement of the handle 17 about a predetermined arc, the gauge plate 10 may be moved toward and away from the cutting plane of the knife in order to gauge slices of a variety of desired thicknesses.

20 indicates a work support or carriage movably mounted for example on tracks 21 and 22 which are effective to guide it across the face and past the cutting edge of the knife. Any suitable means, manual or otherwise, may be employed for urging the work toward the cutting plane and against the gauge plate 10. I illustrate guiding flanges 23 and 24, and it will be understood that the normal thrust of the work is along a path 20 or axis which is generally perpendicular to the cutting plane and to the face of the gauge plate 10, as shown by the arrow A in Figs. 2 and 3.

I find it advantageous to have the guiding means for the gauge plate located at or below the lower edge of the plate. This, however, has the disadvantage of permitting a certain flexure or unintended rearward movement or deformation of the gauge plate in response to the thrust of the work along the axes A. I therefore provide additional means located at or adjacent the upper edge of the gauge plate for preventing any unintended lateral movement or bending of the plate, while permitting normal movement of the plate in response to actuation of the handle 17.

Referring for example to Figs. 2 and 3, I illustrate a bar 30 secured to an opposite portion 31 of the base or frame structure of the machine, which may be an extension or part of the member 2. The member 30 may be secured in position, for example by screws 32 or any other suitable securing means, preferably in such fashion as to permit an adjustment of the member 30 in relation to the edge and the path of movement of the gauge plate 10. At its outer end is an offset portion or flange 33 having a bearing face 34 which engages an opposite bearing face 35 located adjacent or at the upper edge of the gauge plate 10. It is located also closely adjacent the cutting arc of the knife whereby, at the precise point where accurate gauging is important, the gauge plate is positively held in the proper gauging position.

The opposed faces 34 and 35 are in parallelism with the axes of the guiding pins 15 and 16, whereby in response to movement of the handle 17 the gauge plate moves backward or forward without any hindrance from the flange 33. However, since the pins 15 and 16 and the opposed bearing surfaces 34 and 35 are inclined in rela-

tion to the axis of thrust A, the thrust of work against the gauge plate is not effective to bow or bend the gauge plate back out of position, and the very member 33 which serves as a guide for intended movement in parallelism with the pins 15, 16 also serves as an abutment for preventing unintended rearward movement in response to thrusts along the axes A.

Referring to Fig. 4, I illustrate a variant form 10 in which a member 40 is adjustably secured to the cover 41 of the slicing machine, as for example by the screws 42. It might of course be made integral with the cover 41 if desired. It includes a cylinder 43 having an inner bearing 15 surface 44 which receives a plunger 45 spring thrust by the spring 46 into the position in which it is shown in Figs. 4 and 5. 47 is any suitable knob or limiting abutment, secured to the upper end of the shaft 48, which constitutes an upward 20 extension of the plunger proper 45. The plunger 45 is provided with a conic-faced bottom head 49 which is yieldingly thrust into engagement with the upper edge of the gauge plate 10.

Referring to Fig. 6, which illustrates a further 25 variation, in place of the conic head 49 a wedge-shaped head 50 is employed, having a positioning guide or stabilizing member 41 upwardly extending along the outer wall of the member 43, in order to prevent rotation of the member 50. In 30 the forms of both Figs. 4 and 6, a limit member is yieldingly downwardly thrust against the upper edge of the gauge plate 10, which steadies and supports the upper edge of the gauge plate.

In relation to the forms of Figs. 4 and 6, it is 35 important that the angle of the members 49 and 50 respectively and its relation to the compression or thrust of the spring 46 is such that the members 49 or 50 will not interfere with the normal adjustment of the gauge plate, but will still provide sufficient friction or resistance to prevent 40 the bowing or springing of the plate due to the thrust of the work against the forward face of the gauge plate.

It will be realized that whereas I have described 45 and illustrated a practical and operative device, nevertheless many changes may be made in the size, shape, number and disposition of parts without departing from the spirit of my invention. I therefore wish my description and drawings to be taken as being in a broad sense illustrative or diagrammatic, rather than as limiting me to my precise showing.

I claim:

1. In a slicing machine, a base, a knife and 50 means for actuating it, a carriage, means for guiding the carriage across the face and past the cutting edge of the knife, means for guiding material on said carriage for movement toward the cutting plane of the knife, along a path 55 generally perpendicular to the cutting plane, a gauge plate and means for guiding it for movement along a path inclined to the cutting plane and inclined to the path of material on the carriage, including supporting and guiding means 60 adjacent one edge of the gauge plate, and additional supporting and guiding means for said gauge plate, remote from said supporting means, including a member having a bearing surface generally parallel with the path of movement of the gauge plate and inclined to the path of movement of the material, and a member slidably 65 opposed to said bearing surface and associated with the gauge plate, and extending to the rear thereof at all positions of the gauge plate, and means for yieldingly thrusting said member against the edge of the gauge plate along a path generally parallel with the face of the gauge 70 plate.

ciated with the gauge plate, and extending to the rear thereof at all positions of the gauge plate.

2. In a slicing machine, a base, a knife and 5 means for actuating it, a carriage, means for guiding the carriage across the face and past the cutting edge of the knife, means for guiding material on said carriage for movement toward the cutting plane of the knife, along a path 10 generally perpendicular to the cutting plane, a gauge plate and means for guiding it for movement along a path inclined to the cutting plane and inclined to the path of material on the carriage, including supporting and guiding means adjacent the lower edge of the gauge plate, and 15 additional supporting and guiding means for the upper edge of said gauge plate, including a member having a bearing surface generally parallel with the path of movement of the gauge plate and inclined to the path of movement of the material, and a member slidably opposed to said bearing surface and associated with the gauge plate, and extending to the rear thereof at all 20 positions of the gauge plate.

3. In a slicing machine, a base, a knife and 25 means for actuating it, a carriage, means for guiding the carriage across the face and past the cutting edge of the knife, means for guiding material on said carriage for movement toward the cutting plane of the knife, along a path 30 generally perpendicular to the cutting plane, a gauge plate and means for guiding it for movement along a path inclined to the cutting plane and inclined to the path of material on the carriage, including supporting and guiding means 35 adjacent one edge of the gauge plate, and additional supporting and guiding means for said gauge plate, remote from said supporting means, including a member having a bearing surface generally parallel with the path of movement of the gauge plate and inclined to the path of movement of the material, and a member slidably 40 opposed to said bearing surface and associated with the gauge plate, and extending to the rear thereof at all 45 positions of the gauge plate, and yielding supporting means for said member.

4. In a slicing machine, a base, a knife and means for actuating it, a carriage, means for guiding the carriage across the face and past the cutting edge of the knife, means for guiding material on said carriage for movement toward the cutting plane of the knife, along a path 50 generally perpendicular to the cutting plane, a gauge plate and means for guiding it for movement along a path inclined to the cutting plane and inclined to the path of material on the carriage, including supporting and guiding means adjacent one edge of the gauge plate, and additional supporting and guiding means for said gauge plate, remote from said supporting means, 55 including a member having a bearing surface generally parallel with the path of movement of the gauge plate and inclined to the path of movement of the material, and a member slidably 60 opposed to said bearing surface and associated with the gauge plate, and extending to the rear thereof at all 65 positions of the gauge plate, and means for yieldingly thrusting said member against the edge of the gauge plate along a path generally parallel with the face of the gauge 70 plate.

WILLIAM J. CAMPBELL.
